UNITED STATES PATENT OFFICE.

ALBERT B. RIGGINS, OF TREZEVANT, TENNESSEE, ASSIGNOR OF ONE-FOURTH TO JACOB B. LONGWORTH AND ONE-FOURTH TO WILLIAM H. BROWNING, OF ATWOOD, TENNESSEE.

RAIL TIE AND FASTENER.

1,123,923.

Specification of Letters Patent.

Patented Jan. 5, 1915.

Application filed August 8, 1914. Serial No. 655,949.

To all whom it may concern:

Be it known that I, ALBERT B. RIGGINS, a citizen of the United States, residing at Trezvant, in the county of Carroll and State of Tennessee, have invented certain new and useful Improvements in Rail Ties and Fasteners, of which the following is a specification, reference being had to the accompanying drawings.

- 10 This invention relates to new and useful improvements in combined rail ties and fasteners, and an object thereof is to simplify devices of this character and render the same more efficient and durable in use.
- 15 Another object of this invention is the provision of a combined rail tie and fastener, in which the tie is provided with seats to receive the rails, the tie also having clamping members detachably connected thereto for engagement with the rails to detachably connect the same to the tie.

With these and other objects in view, my invention consists in the novel construction, combination, and arrangement of parts, to 25 be hereinafter more fully described, claimed, and illustrated in the accompanying drawing, in which—

Figure 1 is a side elevational view partly in section of my improved device; Fig. 2 is 30 a sectional view on the line 2—2 of Fig. 1; Fig. 3 is a sectional view on the line 3—3 of Fig. 1; and Fig. 4 is a bottom plan view of one of the clamping members.

Referring more particularly to the drawing, the numeral 1 designates a tie constructed in accordance with my invention.

Formed in the upper face of the tie adjacent its opposite ends are recesses 2 and projecting inwardly from the ends of the tie to extend over the outer ends of the recesses are overhanging lips or tongues 3, which are adapted to engage the outer base flanges of the rails 4. The base wall of each of the recesses at its inner end is raised 45 as at 5 to provide a shoulder 6 at the juncture of the raised portion and the body portion of the recess, and a shoulder 7 at the juncture of the raised portion with the body of the tie. The body portion of each recess 50 is provided with a longitudinal groove 8 therein which extends from a point adjacent the shoulder 6 to the outer extremity of the recess below its overhanging lip 3 and is provided with a concaved base wall 9.

55 Formed in the raised portion 5 of each

of the recesses, is an outwardly opening pocket 10, and extending through the tie on opposite sides of the pocket are vertical openings 11 for a purpose to be hereinafter more fully described.

Mounted in each of the recesses is a clamping member 12, each of the clamping members being cut away on its under face at its outer end to provide an overhanging lip 13 for engagement with the inner base flange of its respective rail. The under face of each clamping member at its inner end is cut away to provide a reduced portion 14 and a shoulder 15 at the juncture of the reduced portion with the main portion of the member, the reduced portion 14 being adapted to rest upon the raised portion 5 of its respective recess, and the inner extremity of the clamping member is adapted to engage against the shoulder 7, the reduced portion 14 at its juncture with the body of each member is provided with a central lug 16 for an engagement in the pocket 10 of its recess, the shoulder 15 being adapted to engage against the shoulder 6 of the recess whereby an interlocking joint is formed between the clamping member and the recess.

Formed on the lower face of each locking member at its outer end is an outwardly projecting tongue 17, the under face of which is curved as at 18 to conform to the curvature of the concaved base wall 9 of the groove in each recess, the tongues being of substantially the same length as the grooves, and being adapted to extend under the base flanges of the rails. Each of the clamping members is provided with a pair of openings 19 which register with the openings 11 in the tie, to receive the bolts, screws, or other similar fastening devices 20 by means of which the clamping members are secured to the tie to lock the rails thereto.

As shown in Fig. 1 of the drawing, the under faces of the overhanging lips 3 are beveled to conform to the angle of inclination of the upper faces of the outer base flanges of the rails, and the grooves 8 are extended outwardly slightly beyond the lips 3, to provide downwardly facing shoulders 21 against which the extremities of the tongues 17 engage, whereby rocking of the rails 4 is prevented should the fastening members 20 become slightly loosened. By 110

this construction, the clamping members are engaged against the tie both above and below the rails, so that the base flanges are engaged on their upper and under faces by 5 the clamping members.

In the practical use of my improved tie and fastener, the rails 4 are placed upon the tie so that the overhanging lips 3 engage the outer base flanges of the rails, where- 10 upon the clamping members are placed in position, by holding the same vertical and placing the outer extremities of the tongues 17 in the inner ends of the grooves 8, and moving the clamping members downwardly 15 and outwardly so as to slide the tongues within the grooves to extend beneath the rails, so that the lips 13 engage the inner base flanges of the rails, and the lugs 16 en- 20 gage in the pockets 10. When the clamping members are in this position, the fastening devices 20 are disposed in the registering openings 19 and 11 to securely lock the clamping members to the tie whereby the rails are held in position on the tie between 25 the lips 3 and 13.

From the above description taken in connection with the accompanying drawing, it will be seen that I have provided an improved tie and fastener which is extremely 30 simple in construction, and by means of which the rails of the track may be quickly secured in operative position, or released from the tie.

Having thus fully described my invention, what I desire to claim and secure by 35 Letters Patent is:

1. The combination with a rail tie having elongated recesses formed in its upper face adjacent its ends, said tie having inwardly 40 extending overhanging lips projecting above the outer ends of said recesses and adapted for engagement against the outer base flanges of the rails, each of said recesses having a longitudinal groove formed in its 45 base wall, said groove extending from points adjacent the inner ends of the recesses to points slightly beyond the outer ends of the overhanging lips to provide downwardly

facing shoulders, of clamping members adapted for engagement in said recesses, 50 said clamping members being formed with overhanging lips for engagement with the inner base flanges of the rails, and said clamping members having outwardly projecting tongues formed on their lower faces 55 for engagement within the grooves below the rails, the free extremities of said clamping members being adapted to engage beneath said downwardly facing shoulders.

2. The combination with a rail tie having 60 recesses formed in its upper face adjacent its ends, said tie being formed with overhanging lips extending above the outer ends of the recesses for engagement against the outer base flanges of the rails, each of 65 said recesses having a longitudinal groove formed in its base wall and extending under said overhanging lips, the inner ends of the base walls of said recesses being formed with raised portions to provide outwardly 70 facing shoulders, the raised portion of each recess being formed with an outwardly opening pocket, of clamping members adapted for engagement in said recesses, the under faces of said clamping members being 75 cut away at their inner ends to provide reduced portions for engagement against the raised portions of the base walls of said recesses, the reduced portions of said clamping members forming shoulders for engagement 80 against the shoulders formed by the raised portions of the base walls of the recesses, the reduced portion of each clamping member being formed at its juncture with the body portion of the member with 85 a central lug, said lugs being adapted for engagement in said pockets, and outwardly extending tongues formed in the under faces of said clamping members for engagement in said grooves below the rails.

In testimony whereof I hereunto affix my signature in the presence of two witnesses.

ALBERT B. RIGGINS.
